UNITED STATES PATENT OFFICE.

JOHN NELSON MATLOCK, OF BROOKLYN, NEW YORK, ASSIGNOR TO THE
A. A. GRIFFING IRON COMPANY, OF JERSEY CITY, NEW JERSEY.

DESIGN FOR A RADIATOR.

SPECIFICATION forming part of Design No. 24,367, dated June 4, 1895.

Application filed April 25, 1895. Serial No. 547,196. Term of patent 7 years.

To all whom it may concern:

Be it known that I, JOHN NELSON MATLOCK, a citizen of the United States, residing at Brooklyn, in the county of Kings and State of New York, have invented and produced a new and original Design for Radiators; and I do declare the following to be a full, clear, and exact description of the same, reference being had to the accompanying drawings, forming a part thereof.

The design is shown in the accompanying drawings, in which—

Figure 1 is a view in perspective of a radiator section or loop embodying my design, and Fig. 2 is an enlarged cross-sectional view of the same.

This design consists of a radiator section having two substantially elliptical legs 1 which are so disposed with reference to each other as to present to the eye of the observer the form of a letter **U**, the whole having the configuration shown. The extremities of the legs are united by a web 2 one of the flat sides 3 of which constitutes a portion of an end face 5 of the section. The other portions of this end face are the curved surfaces 4 of the extremities of the legs which, when viewed from one side, are seen to be of circular form at 5 and to merge into the bodies of the respective legs. Continuing along each of the legs from these circular portions are two series of par-

allel, alternating and symmetrically arranged flanges 6. One of these series is composed of flanges each of which is separated in the middle by a space and is therefore not continuous. The outer portion of one of these series merges into a rib 7 extending along the edge of each leg substantially throughout its entire length. The other and alternating series of flanges occupies and somewhat overlaps the space above referred to between the separated portions of the first mentioned series of flanges. This arrangement of these two series is substantially continued upon the end 8 of the section which unites the two legs, except that a lug 12, of slightly greater height than the flanges, takes the place of one part of the last flange on the end of the section. The surfaces of the section between all the flanges and elsewhere are smooth and devoid of ornamentation.

Having thus fully described my design, what I claim is—

The design for a radiator as herein shown and described.

In testimony whereof I affix my signature in presence of two witnesses.

JOHN NELSON MATLOCK.
